[57] **CLAIM**

The ornamental design for a container for a measuring tape, as shown and described.

DESCRIPTION

FIG. 1 is a perspective view of the top and side of the present invention, with a portion of a measuring tape shown in broken lines.

FIG. 2 is a side elevation view of the invention shown in FIG. 1.

FIG. 3 is a top plan view of the invention shown in FIG. 1; and,

FIG. 4 is a bottom plan view of the invention shown in FIG. 1.

The broken line showing is for illustrative purposes only and forms no part of the claimed design.
